[57] CLAIM

The ornamental design for a utility apron, as shown and described.

DESCRIPTION

FIG. 1 is a frontal perspective view of a utility apron showing my new design;

FIG. 2 is a front elevational view thereof;

FIG. 3 is a rear elevational view thereof; the broken lines being understood to represent conventional stitching;

FIG. 4 is an end elevational view thereof as seen from the right-hand end of FIG. 2; and,

FIG. 5 is an elevational view thereof as seen from the left-hand end of FIG. 2, the bottom being planar and unadorned.

FIG. 1

FIG. 2

FIG. 4

FIG. 3

FIG. 5
